Attorney

UNITED STATES PATENT OFFICE.

JOHN F. GRESSLE, OF HAMILTON, OHIO.

TREE-SEAT.

SPECIFICATION forming part of Letters Patent No. 323,415, dated August 4, 1885.

Application filed May 7, 1885. (No model.)

To all whom it may concern:

Be it known that I, JOHN F. GRESSLE, of Hamilton, Butler county, Ohio, have invented certain new and useful Improvements in Tree-5 Seats, of which the following is a specification.

This invention pertains to a seat for use in combination with the trees of a lawn, park, or picnic ground.

10 The invention will be readily understood from the following description, taken in connection with the accompanying drawings, in which—

Figure 1 is a plan of a tree-seat embodying 15 my improvement, a number of the wooden sectors forming the seat proper being omitted, so that the metal work below may be exposed; Fig. 2, a half-vertical section and half-elevation of the same, and Fig. 3a bottom view 20 of one of the seat-boards.

In the drawings, A indicates a flat ring, 25 formed of cast-iron, in segments bolted or otherwise secured together; B, a joint of separation where two contiguous segments are united; C, a downwardly-projecting flange at the inner margin of the ring; D, an ornamental skirting cast upon the periphery of the ring; E, radial slots through the metal of the ring; F, lugs projecting upward from the 30 face of the ring and disposed at the periphery of the ring in line with the slots; G, holes through the metal of the ring, serving to lighten the casting; H, sector-shaped pieces of wood forming a flat circular series disposed upon 35 the top of the metal ring and forming the seat proper; J, bolts engaging through the seat-boards and the slots of the ring; K, a longitudinal groove in the under side of each seat-board, adapted to engage the lugs F; L, cast 40 legs secured to the periphery of the ring-casting, as by bolting, riveting, or by tenoning after the manner of stove-legs; M, leg-screws having foot-pieces cast or otherwise secured to their lower ends and engaging upward 45 within the legs; N, nuts for the screws M, set in transverse mortises cast in the legs; O, the central aperture in the seat proper for the reception of the tree, and P the tree-receiving 50 central aperture of the ring-casting.

50 The seat is to be applied as follows: The ring is opened at two of its joints, and then reconnected around the tree. The seat-boards are then applied and adjusted inwardly to fit

the tree, and the bolts screwed up with sufficient force to hold the seat-boards to the casting without interfering with the outward radial movement of the boards as the tree increases in size. The leg-screws are then adjusted to bring the seat to the proper height, each leg-screw being adjusted with reference 55 to the inequality of the ground at the foot of the tree. As the tree grows the seat-boards are forced outward, and the seat is kept properly leveled by occasional adjustment of the leg-screws to compensate for irregularities 60 in ground-surface produced by the swelling growth of the roots of the tree. The seat-boards are guided in their radial travel by the bolts engaging the slots and by the lugs engaging the groove. When the growth of the tree 65 has expanded the seat as far as is thought desirable, the inner ends of the seat-boards may be sawed off and the sectors again set inward; or new seat-boards, of the desired length, may be applied, and the older and longer boards 70 may be applied at a smaller tree.

I claim as my invention—

1. In a tree-seat, the combination, with a ring and its supporting-legs, of a circular series of sector-shaped seat-boards secured to 80 said ring, as by means of bolts engaging in radial slots, and adapted to move radially outward as the tree expands in growth, substantially as set forth.

2. In a tree-seat, the combination of a 85 radially-slotted ring-piece, a circular series of sector-shaped seat-boards secured thereto, and vertical extensible legs secured to the ring-piece, substantially as and for the purpose set forth.

3. In a tree-seat, the combination of ring A, 90 having slots E and lugs F, supporting-legs secured to the same, and sector-shaped seat-boards H, provided with guide-grooves K, and secured to the ring by bolts J, substantially as and for the purpose set forth.

4. In a tree-seat, the combination of radially-slotted ring A, sector-shaped seat-boards H, secured thereto, legs L, secured to the ring, and footed screws M, engaging the legs, substantially as and for the purpose set forth.

JOHN F. GRESSLE.
